CONTINUOUS INDUCTIVE TRAIN CONTROL SYSTEM

Application filed October 30, 1925. Serial No. 65,816.

This invention relates to automatic train control systems of the continuous inductive type, and more particularly concerns a method of conditioning the car-carried apparatus of such a system for train operation over a section of trackway which is not equipped for train control.

The present application is a continuation in part of applicant's co-pending application Ser. No. 717,767, filed June 4, 1924.

In applying a system of automatic train control to a railway system, it is necessary to provide for the operation of trains equipped for train control over sections of trackway not equipped for train control operation. In the continuous inductive type of train control system, in which currents flow in the track rails continuously under favorable traffic conditions and are cut off under unfavorable traffic conditions, and in which influences corresponding to these currents are inductively received by the moving vehicle, a method has been devised for placing the car-carried control apparatus in its non-control condition as the train enters unequipped sections of trackway which is commonly known as the excess energy loop method. In this scheme, an excess amount of current is supplied from the trackway for short distances of vehicle travel at points where the vehicle is about to enter unequipped territory, and means are provided on the locomotive for placing the automatic equipment in its inactive condition only if the receiving equipment receives a given amount of energy with its sensitivity substantially reduced or diminished by some suitable manually actuatable means under the control of the engineer, the amount of energy supplied by the excess energy trackway loop being the only amount supplied to the receivers which is sufficient to accomplish this result.

Ordinarily, alternating currents of commercial frequencies are used to transmit the control influences from the trackway, these currents being impressed on the track rails at one end of each of the usual track blocks. On certain railway systems however, and particularly on railways employing electri-

cal current for propulsion purposes and using the track rails as a return, it is necessary or advisable to use currents of frequencies higher than the usual commercial frequencies for train control purposes, so that the propulsion current can be more readily filtered out by the car-carried receiving apparatus of the train control equipment. When currents of comparatively high frequency are impressed upon the track rails at one end of a block, the current flowing in the track rails of the block will vary greatly at different points in the block due to the reactance of the track rails, the leakage between the rails and for various other reasons. This variation in control current in the track rails of a single block is very great, sometimes running as high as twenty times as much current flowing in the rails at the point where the energy is impressed as is flowing in the rails at the opposite end of the block.

It is apparent that when the excess energy method of conditioning the car-carried train control equipment for operation in unequipped territory is employed on railways using high frequency train control currents, the car-carried receiving and control equipment must perform its various functions of control and of being rendered inactive for travel over unequipped sections of trackway within very narrow margins of energy supply. For example, assuming that the maximum amount of energy available along the trackway is represented by 30 units, that 20 units are supplied to the track rails at one end of each block, and that 30 units are supplied to the excess energy loop or section at the entrance to unequipped territory, then the car-carried receiving and control equipment must respond properly to energy varying from one unit at one end of each block to 20 units at the other, and when the sensitivity of the receivers is reduced to render the apparatus inactive, the apparatus must not respond to 20 units but must respond to 30 units to be set in the inactive state. In actual practice, the energy supply in the various blocks and at the various excess energy points varies to a certain extent so that

the theoretical problem set forth above is magnified, and the limits within which the control apparatus must operate distinctively are very narrow.

5 With the above and other considerations in mind, it is proposed in accordance with the present invention to provide a train control system of the continuous inductive type in which the excess energy method of placing the car-carried apparatus in its inactive condition is used, and in which the car-carried apparatus is provided with novel means for causing its distinctive operation in response to variations in sensitivity and to 10 comparatively small differences in energy supply. More specifically, it is proposed to provide a system of the type described in which a transformer is employed in a tuned vehicle receiving circuit and in which the 15 voltage transformation ratio of the transformer and the tuning of the receiving apparatus is changed to diminish the sensitivity of the receiving equipment to a definitely fixed degree when the vehicle is passing over 20 an excess energy section preparatory to entering unequipped territory.

It is further proposed to provide a system of the type described employing a suitable car-carried relay for responding to the control circuits in the track rails in which the proper operation of such relay is checked at every point where the vehicle enters unequipped territory, the complete operation of such relay at these points being necessary 35 to render the car carried control equipment inactive.

Other objects, advantages and characteristic features of the invention will be pointed out and will become apparent as the description thereof progresses.

In describing the invention in detail, reference will be made to the accompanying drawings in which:

Fig. 1 represents in a diagrammatic and conventional manner, the car-carried apparatus for a train control system embodying the present invention, together with a typical arrangement of trackway devices and circuits for use therewith;

50 Fig. 2 shows a modified method of reducing the sensitivity of the receiving and amplifying apparatus of a train control system, and

Figs. 3 and 4 show further modifications 55 of a means for reducing the sensitivity of the car-carried receiving equipment.

Referring more particularly to Fig. 1, the usual wayside apparatus for an automatic train control system of the continuous inductive type has been shown, together with an excess energy section and a portion of trackway which is unequipped for automatic train control. This trackway equipment is well known to those skilled in the art and 65 has been described in detail in the applica-

tion of Charles S. Bushnell, Ser. No. 723,048, filed June 28, 1924 and for this reason only a very brief description of this equipment will be given. The track rails 1 are shown divided into blocks by the usual insulating joints 2, the block I, the adjacent end of the block H, and excess energy section J, and a portion of a block K in non-train control territory having been shown. As certain of the devices used in the several blocks are substantially identical, like reference characters having distinctive exponents have been used to designate the corresponding elements in these blocks.

The usual track batteries 3 are connected across the track rails 1 at the exit ends of the blocks as shown, and energize the well known track relays T, connected across the track rails at the entrance ends of the blocks. The usual alternating train control current is supplied to the two track rails in series at the exit end of each block through the transformers 4 connected in series with the track battery 3 as shown. The transformers 4 are energized through the front contacts 5 and 6 of the track relays T from a second transformer 7 connected across a transmission line 8. It is evident that this train control current, usually termed the track phase current, will be supplied to the two track rails of a block in series so long as the track relay at the entrance end of the next block in advance remains energized, or in other words, so long as no train is located in such advance block.

The rails of the excess energy section J are constantly supplied with alternating current from the transformer 9, this transformer supplying a larger amount of current to the rails of this section than is supplied by the transformer 7. It should be understood that wave wires of the well known type, lying parallel to the track rails and in close proximity thereto, might be employed to carry this excess current in place of the track rails if desired, the resultant magnetic field for transmitting influences to the vehicle carried receiving apparatus being obviously the same in either case. An alternating current track relay 10 is connected across the track rails at the entrance end of the excess energy section J, and acts with the track relay T' at the entrance end of the first block K of the unequipped or non-train control territory, to control the energization of a line relay 11 through a circuit which is obvious from the drawings.

The line relay 11 controls the energization of the transformer 4 supplying track phase train control current to the track rails of the block I. The purpose of this arrangement is to provide adequate automatic train control up to the point at which unequipped or non-control territory is entered. If, for instance, a train were located near the en-

trance end of the block K and a train approached in the block I, in train control territory, the proper automatic control should be imposed to bring the train in 5 block I to a stop before it could enter the block K. This arrangement of controlling the train control current in the last block of the equipped trackway in accordance with traffic conditions in the first block of un- 10 equipped trackway may be dispensed with if desired, but it is thought preferable to employ this additional protective control for the reason that the engineer, while traveling in equipped territory, is inclined to 15 expect full protection through the automatic equipment. Obviously if the last block of equipped trackway were not controlled in accordance with traffic conditions in the first unequipped block, the automatic control apparatus 20 might under certain conditions indicate clear traffic conditions ahead when such conditions do not in fact exist.

Wayside signals of the semaphore, color light, or other suitable type may or may not 25 be used in connection with the trackway equipment. In the drawings, semaphore wayside signals Z of the usual type have been illustrated in a conventional manner only, a showing of their operating devices 30 and connections being omitted as these devices form no part of the present invention and are well understood by those skilled in the art.

As the method of rendering the car-carried apparatus inactive for travel over trackway which is unequipped for train control, which comprises the present invention, is particularly applicable to railways employing electrical current for propulsion 35 purposes and returning this current through the track rails, the trackway equipment has been shown arranged for electrical propulsion. Impedance bonds 12 of the well known type are connected across the track rails at 40 each end side of the insulating rail joints 2, and these impedance bonds are connected together at their midpoints to conduct the propulsion current past these joints. An alternating current generator G has been 45 shown connected between the track rails 1 and a trolley wire 13, the connection between the generator and the track rails being through a balanced impedance coil 14. It should be understood that this showing 50 of the electrical propulsion equipment is illustrative only, and that a third rail or other suitable system of propulsion current supply might be used without departing from the spirit of the invention.

Referring now more particularly to the car-carried equipment, a railway vehicle has been conventionally illustrated in the block H by the wheels and axles 15, the normal direction of vehicle travel being indicated 55 by the arrow. A propulsion motor 16, con-

nected between the vehicle axles and a trolley 17 engaging the wire 13, has been shown diagrammatically in connection with the vehicle. Two receiving coils, 18 and 19, which may or may not be provided with laminated 70 iron cores, are carried in front of the leading axles of the vehicle, and in inductive relation to the track rails 1. These receiving coils are connected in such a manner that the voltages induced therein by currents flowing in opposite directions in the two track rails are cumulative. The receiving coils 18 and 19 are connected to an audion tube amplifier of the type now common 75 in train control practice, through a filter circuit. This filter circuit is of the type shown and described in my co-pending application Ser. No. 717,767, filed June 24, 1924 of which the present application is a continuation in part, and consists of an 80 input circuit comprising a condenser 20 and a reactance coil 21, preferably iron cored, connected in series with the primary winding of an auto transformer 22. The secondary winding of the auto transformer 22 85 is connected across a variable condenser 23 and to the input circuit of the amplifier through the back contact 24 and contact finger 25 of the push button relay 26.

The amplifier is of a type well known 90 to those familiar with train control practice, and as its particular construction forms no part of the present invention and has been described in detail in my co-pending application, identified above, a detailed description thereof will not be given. The usual 95 three-element audion tubes 27 are used in the amplifier, and reactance coupling of the well known type has been provided between them, the iron cored reactance coil 28 being 100 employed. The filaments 29 of the tubes 27 are connected in series and the current through them is limited by the resistances 30 and the ballast lamp 32. The plate and filament 105 circuits are energized by the batteries 33 and 34 respectively in the usual manner as clearly shown.

The push button relay 26 is used merely for repeating the operation of a push button 35, which is located at some convenient point in the locomotive cab, the relay 26 being usually carried in a suitable relay housing on the tender or other suitable point together with the other relays and devices 110 of the car-carried control equipment.

The car-carried apparatus includes a main relay MR, a secondary relay S and a non-control relay NC. These relays are preferably of the direct current type and are suitably constructed and balanced to withstand 115 the vibration and shock of railway usage. The secondary relay S and the non-control relay NC are made slow acting by some suitable means, for drop-away, the purpose 120 of this slow acting feature being brought 125 130

out in connection with the description of the operation of the system.

The vehicle brakes may be controlled in any suitable manner and by means of any one of a number of well known devices used for this purpose. As the initiation of an automatic brake application is usually effected by the de-energization of some suitable electro-pneumatic valve, cam starting magnet or other electro-magnetic device, a normally energized brake applying device has been conventionally illustrated at BA, it being assumed that this device will act in some suitable manner to initiate a restrictive brake application when de-energized.

Operation Fig. 1

The circuits and devices have been shown in their normal operating positions in the drawings, that is, their positions are such as would be assumed with a train running under clear traffic conditions over a section of trackway which is equipped for automatic train control.

With clear traffic conditions existing, that is, with no train, broken rail or other hazard in the block in which the train under consideration is located or in the next block in advance thereof, alternating train control current will flow in the two track rails of each equipped block in series, this current being supplied from the transmission line 8 through the transformers 4 and 7 and the contact fingers 5 and 6 of the track relay T, the circuit being obvious from the drawings. This current will induce a voltage in the receiving coils 18 and 19 which will be impressed upon the filter circuit of the car-carried equipment. The input and output circuits of the filter are tuned to the frequency of the train control current, and the voltages induced by the propulsion current which is of a distinctive frequency, flowing in the track rails will therefore be suppressed and voltage of train control frequency only will be impressed on the input circuit of the amplifier. It is sometimes found desirable to improve the tuning of the filter circuit by varying the point at which the primary circuit is connected to the transformer winding. In this connection it should be noted that if the propulsion current is equally balanced in the two track rails, no voltage of propulsion frequency will be induced in the receiving coils, as these coils are so connected that currents flowing in the same direction in track rails will induce voltages which are in opposition in the two coils. Unbalancing of the propulsion current in the track rails frequently occurs, however, and for this reason the filter circuit is used to keep voltages of propulsion frequency out of the amplifier.

The voltages delivered to the amplifier are amplified and impressed on the windings

of the main relay MR through a circuit which may be traced as follows:—from the plate 36 of the last tube 27 of the amplifier, through wires 37 and 38, the winding of the main relay MR, wires 39 and 40, contact finger 41 and back contact of the push button relay 26, and wires 42 and 43 to the filament circuit of the last tube 27 of the amplifier. With the main relay MR thus energized, its contact fingers 44, 45 and 46 are attracted and a circuit for energizing the brake applying device BA is completed, which circuit is obvious from the drawings. With the brake applying device BA energized, the train may proceed without restriction in the clear block. The energization of the main relay MR also causes the energization of the secondary relay S through a circuit which may be traced as follows:—from the battery terminal B, contact finger 47 and back contact of the push button relay 26, wire 48, contact finger 45 and front contact of the main relay MR, wire 49 and winding of the secondary relay S to the battery terminal C. With the secondary relay S energized, its contact fingers 50, 51 and 52 will be attracted.

When the vehicle under consideration enters a caution or danger block, that is, a block in which a train or other hazard is located or the first block to the rear thereof, no train control current will flow in the track rails, the receiving coils 18 and 19 will not have voltages of train control frequency induced therein, the amplifier input circuit will not be energized and the main relay MR will consequently be de-energized, retracting its contact fingers 44, 45 and 46. The retraction of the contact fingers 44 of the main relay MR causes the de-energization of the brake applying device BA and a restrictive brake application results. This brake application is of a nature depending on the particular brake control apparatus used, and may be a single, full service application, a speed distance restriction or any other suitable and well known automatic restriction may be imposed.

Considering now more particularly the operation of the non-control apparatus comprising the present invention, assume that the train under consideration is proceeding in the block I under clear traffic conditions, this being the last block in a section of trackway which is equipped for automatic train control, and that the engineer wishes to condition the car-carried apparatus for travel over an unequipped section of trackway, the first block of which is represented by the block K in the drawings. As the train enters the excess energy section J, the engineer depresses the push button 35 to so retain it throughout such section, thus energizing the push button relay 26 through a circuit which is obvious. The energization of the push

button relay 26 causes its contact finger 25 to be attracted, breaking the back contact 24 and engaging the front contact 53. It is evident from the drawings that the closing of the front contact 53 of the push button relay 26 changes the connections to the input circuit of the amplifier. This change in the input circuit connections reduces the sensitivity of the receiving system for two reasons; first because it changes the input circuit of the amplifier to cause it to be connected across the primary winding of the auto-transformer 22, instead of across the secondary as before, thereby reducing the voltage applied to the input circuit by the ratio of transformation of the auto-transformer; and second, by reason of the fact that the auto-transformer is partially detuned because of the transfer of the condenser 54 from being connected across the secondary to being connected across the primary winding thereof. The values of the capacity of the condensers 23 and 54 are so chosen as to give the desired degree of de-tuning and also are chosen to resonate with the transformer at the frequency used when these two condensers are connected in parallel across the secondary winding of the transformer.

Although the sensitivity of the receiving equipment has been substantially reduced by the change of transformation ratio and the de-tuning described above, the energy flowing in the track rails of the excess energy section J is still sufficient to induce such a voltage in the receiving coils 18 and 19 that the amplifier is maintained energized and its output circuit delivers a normal current. The main relay MR however, is momentarily de-energized for the reason that the circuit connecting this relay with the amplifier output circuit is broken by the attraction of the contact finger 41 of the push button relay 26. The de-energization of the main relay MR retracts the contact finger 45, thereby breaking at a second place the energizing circuit for the secondary relay S, (which was initially broken at contact finger 47 of relay 26, upon closure of 35) which circuit has been traced above. The de-energization of the secondary relay S causes the retraction of its contact finger 50, and when this contact finger engages its back contact, an alternative energizing circuit for the main relay MR is completed, which circuit may be traced as follows:—from the plate 36 of the last tube 27 of the amplifier, through wires 37 and 38, the winding of the main relay MR, wires 39 and 56, back contact and contact finger 50 of the secondary relay S, and wires 57 and 43 to the filament circuit of the amplifier. As soon as the main relay MR is energized, the push button relay 26 being still in its energized condition, and secondary relay S being de-energized, a circuit is completed for energizing the non-control

relay NC, which circuit may be traced as follows:—from the battery terminal B, contact finger 58 and front contact of the push button relay 26, wire 59, contact finger 46 and front contact of the main relay MR, 70 wires 60, contact finger 51 and back contact of the secondary relay S, wires 61 and 62 and the winding of the non-control relay NC to the battery terminal C. Once energized the non-control relay C is maintained energized 75 through a stick circuit, which circuit may be traced as follows:—from the battery terminal B, contact finger 52 and back contact of the secondary relay S, wire 63, contact finger 64 and front contact of the non-control relay NC, wires 65 and 62, and the winding of the non-control relay NC to the battery terminal C. As soon as the non-control relay NC is energized, an energizing circuit for the brake applying device BA is completed 80 through the contact finger 66 and front contact of this non-control relay, this energizing circuit being obvious from the drawings. With the brake applying device BA energized, the train under consideration may 85 proceed through the unequipped section of trackway without restriction, the de-energization of the main relay MR due to the lack of train control current in the track rails of the unequipped trackway having no effect 90 upon the energization of the non-control relay NC, as this relay is maintained energized through a stick circuit including its own front contact and a back contact of the secondary relay S. 95

The relay S, as mentioned above, is designed to be slow to release, but only very slightly slower to release than is relay MR. Thus, when 26 picks up, relays MR and S are simultaneously de-energized at fingers 41 100 and 47 respectively, and S is just slow enough to release to insure that MR releases before S, or, that contact finger 44 breaks contact before contact finger 50 makes contact. This, of course, results in a momentary de-energization of BA, followed by a re-energization, and since at least several seconds is required, in an air brake system, after initiation thereof, for the actual application of the brakes to occur, no brake application here takes place. At the same time, by thus timing relays MR and S, it is insured that depression of push button 35 results in retraction of the fingers of relay MR. 110

Also, as above mentioned, relay NC is slow to release, whereby to insure that BA be not de-energized due to momentary interfering currents of proper frequency during travel through non-train control territory. Assume, for instance, that while traveling through non-train control territory momentary interfering current is encountered such as to result in pick-up of relay MR. This will cause relay S to pick up to thus break 115 120 125 130

the stick circuit of relay NC at contact finger 52. If relay NC were quick to release, it would drop and initiate BA. And subsequent drop away of MR and in turn of S 5 would not complete the pick-up circuit for NC, so that NC would remain de-energized.

However, with NC slow to release, as shown and described, it holds up long enough for MR to drop again, to in turn 10 drop S to thus re-energize NC. Thus such momentary interfering current has no effect on BA.

From the above description of the operation of the car-carried apparatus upon the 15 entrance of a train to non-control territory, it will be observed that it is necessary for the main relay to be completely picked up from its full de-energized position while the sensitivity of the receiving equipment is reduced and the train is traveling over the excess energy section. In the systems previously proposed for rendering the car-carried apparatus inactive by means of an excess energy loop or section, it was merely necessary that the main relay or equivalent device be maintained in its energized position when the amplifier sensitivity was reduced and the excess energy section traversed. It 20 is clear that the arrangement of the present invention insures that the main relay MR is in proper operating condition when the change from equipped to unequipped trackway is made. For example if the contact fingers of the main relay were jammed or 25 stuck in their attracted position it would be possible to temporarily energize the non-control relay NC, since the secondary relay S is de-energized due to contact finger 47 of relay 26 being attracted. Thus relay NC 30 would be energized and thus remove BA from under control of the main relay MR and itself assume control of BA. Immediately however, upon the car entering the 35 non-train control territory, upon manually operable contact 35 being released, relay S would be energized, it being borne in mind that contact finger 45 of relay MR is assumed to be stuck or jammed in attracted position. This 40 energization of secondary relay S would break the stick up circuit for relay NC at contact finger 52 to thereby remove brake applying device BA from under control of the relay NC. Thus in order that relay NC be retained energized during travel 45 through non-train control territory, it is necessary that relay MR first release and subsequently pick up. Also, if for any reason the current supplied by the amplifier were strong enough to maintain the contacts 50 of the main relay MR attracted but not of a sufficient value to move these contacts from their full de-energized to their full energized position, the pick-up circuit for the non-control relay could not be completed for the 55 reason that the contact finger 46 of the main

relay would maintain this pick-up circuit open. The operative condition of the main relay is thus checked at every point where the train passes from equipped to unequipped sections.

70

Referring now to Fig. 2, a modified form of apparatus for decreasing the sensitivity of the car-carried receiving apparatus has been shown. It should be understood that the amplifier shown in Fig. 2 is designed to be used in connection with suitable car-carried and trackway apparatus such as that shown in Fig. 1, a complete showing of this apparatus being omitted for the sake of simplifying the drawings. In this particular modification the reduction of sensitivity obtained in the amplifier and the receiving circuits is based on the fact that in a circuit including a transformer having very poor regulation, if an appreciable current is drawn, the voltage delivered by the transformer will be very greatly reduced.

75

The usual inductive receiving coils 18 and 19 are provided and are connected as shown to the input circuit of a filter which is identical with the filter shown in Fig. 1, its corresponding parts being referred to by the reference characters used in Fig. 1. The output circuit of the filter is tuned by the variable condenser 68, and is connected between the grid and filament of the first tube of the usual audion tube amplifier. A potentiometer comprising the two variable resistances 69 and 70 is connected across the filament battery 34, in such a manner that the bias or degree of potential on the grid circuit may be varied by connecting the grid return from the filter to various points of the potentiometer. This change of connection of the grid return is accomplished by a make-before-break contact finger 71 of the push button relay 26 having a back contact 72 connected to one extreme end of the potentiometer and a front contact 73 connected to its midpoint as clearly shown.

80

In operation, when the train is traveling over trackway equipped for train control operation, the push button relay 26 is normally de-energized and the voltages induced in the receiving coils 18 and 19 are delivered by the filter to the grid filament circuit of the first tube 27 of the amplifier in the usual manner, this circuit being completed through the contact finger 71 and the back contact 72 of the push button relay 26. The voltages are amplified and operate the train control apparatus in the manner described in connection with Fig. 1. When it is desired to decrease the sensitivity of the receiving equipment in order to set up the inactive or non-control condition described above, the push button relay 26 is energized by depressing the push button 35 and the contact finger 71 of this relay is attracted, first engaging its front contact 73 and then

disengaging its back contact 72. When the front contact 73 is closed and the back contact 72 is opened, the grid return circuit of the first tube 27 is connected to a point on 5 the potentiometer which is more positive in polarity than the normal connection through the back contact 72, and for this reason a positive bias is placed on the grid of this tube. It is a well known fact that if a positive bias is placed on the grid of an audion tube, its grid-filament circuit draws a current load instead of the pure voltage which actuates the grid circuit when the grid bias is negative. As the magnetic coupling between 10 the track rails and the receiving coils is very poor, simulating in effect a transformer having a core with a large air gap therein, the current drawn from the receiving circuit when the grid is biased positive will cause the voltage induced in the receiving coils to drop by a large amount, consequently decreasing the voltage supplied to the amplifier, and thereby greatly reducing the sensitivity of the entire receiving equipment. This scheme is, of course, employed 25 in connection with an excess energy section on the trackway of the type described in connection with Fig. 1, and the excess energy supplied causes the output current of the amplifier to be sufficient to energize the main relay MR in spite of the reduced sensitivity due to the positive grid bias.

The degree to which the sensitivity of the receiving equipment is reduced by the apparatus shown in Fig. 2 may be very accurately regulated by adjusting the values of the variable resistances 69 and 70 and thereby adjusting the extent of the positive bias which is placed upon the grid of the first tube. 30 By properly regulating these values of the resistances 69 and 70, a very large but definitely fixed reduction in the sensitivity of the receiving equipment is produced, and proper control is maintained when non- 35 control territory is entered.

Referring now to Fig. 3, a modified method of reducing the sensitivity of the car-carried receiving equipment on a system in which no filter circuit is used has been 40 shown. In this modification, the amplifier has been represented conventionally at A, and the push button relay 26 with its push button 35 and its contact finger 74, controlling the input circuit of the amplifier, has been shown. In this scheme, when the push button relay is de-energized the two receiving coils 18 and 19 are connected in series to the input circuit of the amplifier in the usual manner through a circuit which may 45 be traced as follows: from the receiving coil 18, wires 75 and 76, the input circuit of the amplifier A, wire 77, contact finger 74 and back contact of the push button relay 26, wires 78 and 79, receiving coil 19 and wires 50 80 and 81 to the receiving coil 18. The cir-

cuit just traced is preferably tuned to resonance at the train control frequency by means of the condenser 82 which is connected in parallel with the two receiving coils 18 and 19 as clearly shown.

When it is desired to reduce the sensitivity of the receiving equipment to render the car-carried equipment inactive as described above, the push button relay 26 is energized by depressing the push button 35 and the contact finger 74 engages its front contact. An alternative input circuit for the amplifier A is now completed, which circuit includes only one of the receiving coils and may be traced as follows:—from the receiving coil 18, wires 75 and 76, the input circuit of the amplifier A, wire 77, contact finger 74 and front contact of the push button relay 26 and wires 83 and 81 to the receiving coil 18. It should be observed that the circuit just traced through the receiving coil 18 alone is not tuned to resonance by the condenser 82. It is obvious that the voltage supplied to the input circuit at the amplifier when the push button relay 26 is energized will be approximately half the voltage which is supplied to this input circuit when this relay is de-energized by reason of the fact that only one receiving coil is connected to this receiving circuit when the relay 26 is in its energized condition. In addition to this, the circuit through the single receiving coil 18 is not tuned to resonance and the voltage delivered thereby is therefore in reality less than one-half of the voltage delivered by the two receiving coils 18 and 19 connected in series.

Referring now to Fig. 4, another modified method of reducing the sensitivity of the car-carried apparatus has been shown. It should be understood that this modification is to be used in connection with suitable car-carried and trackway apparatus such as has been shown in Fig. 1, the amplifier and control circuits having been omitted to simplify the disclosure in Fig. 4.

In the modification shown in Fig. 4, the reduction in sensitivity of the receiving circuit is obtained by reducing the primary turns on the transformer 22 to such an extent that the coupling is very loose and very little energy is transferred to the secondary circuit. As shown in Fig. 4, this is accomplished by providing two taps, 95 and 96 on the winding of the transformer 22, the tap 95 being connected to a point on the transformer winding which gives normal secondary voltage when operating in train control territory, and the tap 96 being connected to a point on the winding where the coupling is so low that no appreciable secondary voltage results unless excess energy is supplied to the receiving coils 18 and 19. The taps 95 and 96 are connected as shown 125 to the back and front contacts respectively 130

of the push button relay 26, the contact finger 25 of which is connected through the impedance coil 21 and the condenser 20 to one side of the receiving circuit as shown. 5 The usual tuning condenser 23 is provided across the secondary circuit of the transformer 22, and the wires 97 and 98 are assumed to be connected to the grid and filament, respectively, of the first tube of an 10 amplifier as shown in Fig. 1.

In operation, when the push button 35 is depressed and the relay 26 energized, the contact finger 25 is raised to engage its front contact, thereby connecting the receiving 15 circuit to the tap 96 of the transformer 22. If at this point the vehicle is travelling over an excess energy section, as the section J of Fig. 1, the energy supplied to the receiving circuit through the coils 18 and 19 is 20 sufficient to energize the main relay MR through the amplifier and to set up non-control conditions in the car-carried apparatus as described in connection with the operation of the system shown in Fig. 1. If, 25 however, the relay 26 is energized when the usual train control current is flowing in the track rails under the train, the main relay MR is not energized because of the extremely loose coupling of the transformer 22 with 30 the input circuit connected to the tap 96, and non-control conditions cannot be set up.

From the foregoing description it will be seen that a method of rendering inactive the car-carried equipment of an automatic train 35 control system of the continuous inductive type has been provided in which the sensitivity of the receiving apparatus is substantially reduced by a fixed and definite amount in a novel and convenient manner, and that 40 suitable equipment has been provided to operate either under conditions of electrical propulsion or with the usual unelectrified trackway systems.

Although the particular method of rendering the car-carried equipment inactive and of reducing the sensitivity of the receiving equipment which comprises the present invention has been described in a rather specific manner and in connection 45 with a single specific train control system, it should be clearly understood that certain changes, additions and modifications may be made within the scope of the present invention. For instance, the system of the 50 present invention is readily applicable to the well known three-position type of continuous inductive train control, in which case the method of reducing the sensitivity 55 would be applied to the receiving equipment associated with one set of receiving coils only, and various other additions or combinations might be made without departing 60 from the spirit of the invention as defined by the appended claims.

What it is desired to secure by Letters Patent is:—

1. In an automatic train control system of the type in which influences corresponding to traffic conditions are continuously transmitted inductively from the trackway to a moving vehicle, car-carried equipment for controlling the vehicle brakes in accordance with said inductively received influences, and means for rendering said car-carried equipment inactive for vehicle travel over sections of trackway unequipped for train control operation comprising, a section of trackway for transmitting an excessive amount of energy to the vehicle, a receiving circuit on the vehicle including a step-up transformer, means for varying the operative relation of the transformer to the receiving circuit, and further car-carried means whereby said brake control apparatus 85 may be rendered inactive if the sensitivity of said receiving circuit is reduced while said excessive energy trackway section is being traversed.

2. In an automatic train control system 90 for a railway having a portion of its trackway equipped for automatic train control and a portion not so equipped, car-carried brake control apparatus continuously controlled in accordance with energy received 95 from the trackway through receiving equipment including a transformer, a normally de-energized relay acting when energized to change the connections of said transformer in said receiving equipment and thereby reduce the sensitivity of said receiving equipment, a manually actuatable circuit controller for controlling the energization of said relay, means at the entrance to said unequipped portion of trackway for delivering an 100 excessive amount of energy to said receiving equipment, and means for maintaining said brake control apparatus inactive, while traveling in the unequipped portion of trackway, said last mentioned means being 110 actuated if said relay is energized while the vehicle is traversing said excessively energized trackway means and being held actuated only if said relay is returned to its normal de-energized condition.

3. In an automatic train control system 115 for a railway having a portion of its trackway equipped for automatic train control and a portion not so equipped, car-carried means for controlling the vehicle brakes in accordance with influences corresponding to traffic conditions while the vehicle is traveling in said equipped portion and for maintaining the brake control apparatus inactive when traveling in the unequipped portion of trackway comprising, a main relay energized in accordance with control energy received from the track rails by inductive receiving apparatus, a brake control device normally controlled by said main 120 relay, and a circuit controller for controlling the energization of said main relay, the 125 circuit controller being connected to the inductive receiving apparatus and to the main relay, the circuit controller being actuated by influences received from the track rails by the inductive receiving apparatus.

- relay, a manually energizable relay acting when energized to reduce the sensitivity of the inductive receiving apparatus, a secondary relay energized through a back contact of said manually energizable relay and a front contact of said main relay; and a non-control relay having a pick-up circuit including a front contact of said manually energizable relay, a front contact of said main relay and a back contact of said secondary relay, and a stick circuit including a back contact of said secondary relay and a front contact of the non-control relay, said non-control relay acting when energized to maintain said brake control device inactive.
4. In an automatic train control system for a railway having a portion of its trackway equipped for automatic train control and a portion not so equipped, and using alternating current for propulsion purposes, means for controlling the brakes of the vehicle in accordance with influences corresponding to traffic conditions comprising alternating currents of a frequency distinct from the propulsion current frequency flowing in the track rails, a car-carried receiving circuit including a transformer having a primary circuit and a secondary circuit, said circuits being tuned to resonance for the frequency of said train control current, means controlled by said receiving circuit to control the vehicle brakes, and means for rendering said brake control apparatus inactive for vehicle travel over said unequipped portions of trackway comprising, a section of trackway at the entrance to said unequipped portion supplied with an excessive amount of current of train control frequency, a normally de-energized manually energizable relay on the vehicle acting when energized to change the connections of said transformer in the receiving circuit to change the tuning thereof, and the energization of said normally de-energized relay also rendering the means for controlling the vehicle brakes inactive if said relay is energized while the vehicle is traversing said excessively energized trackway section.
5. In an automatic train control system for a railway having a portion of its trackway equipped for automatic train control and a portion not so equipped, a car-carried brake applying device and means for controlling said device in accordance with influences corresponding to traffic conditions inductively received from the trackway in said equipped portion comprising, a main relay and a receiving circuit, a non-control relay acting when energized to maintain said brake applying device inactive in said unequipped portions of trackway, and means whereby said non-control relay is energized only if said main relay is first de-energized and then re-energized.
6. In an automatic train control system of the type in which influences corresponding to traffic conditions are continuously transmitted inductively from the trackway to a moving vehicle, car-carried equipment for controlling the vehicle brakes in accordance with said inductively received influences, and means for rendering said car-carried equipment inactive for vehicle travel over sections of trackway unequipped for train control operation comprising, a section of trackway for transmitting an excessive amount of energy to the vehicle, a receiving circuit on the vehicle, a main relay in the receiving circuit normally controlling the brake control apparatus and a secondary relay controlled by the main relay and in turn controlling a circuit through the main relay.
7. In an automatic train control system of the type in which influences corresponding to traffic conditions are continuously transmitted inductively from the trackway to a moving vehicle, car-carried equipment for controlling the vehicle brakes in accordance with said inductively received influences, and means for rendering said car-carried equipment inactive for vehicle travel over sections of trackway unequipped for train control operation comprising, a section of trackway for transmitting an excessive amount of energy to the vehicle, a receiving circuit on the vehicle, a main relay in the receiving circuit normally controlling the brake control apparatus, a secondary relay controlled by the main relay and in turn controlling a circuit through the main relay, and a non-control relay arranged to be operated to assume control of the brake control apparatus.
8. In an automatic train control system of the type in which influences corresponding to traffic conditions are continuously transmitted inductively from the trackway to a moving vehicle, car-carried equipment for controlling the vehicle brakes in accordance with said inductively received influences, and means for rendering said car-carried equipment inactive for vehicle travel over sections of trackway unequipped for train control operation comprising, a section of trackway for transmitting an excessive amount of energy to the vehicle, a receiving circuit on the vehicle, a main relay in the receiving circuit normally controlling the brake control apparatus and a secondary relay controlled by the main relay and in turn controlling a circuit through the main relay, and a non-control relay controlled jointly by the main relay and the secondary relay to cause the non-control relay to assume control of the brake control apparatus.
9. In an automatic train control system for a railway having a portion of its track-

- way equipped for automatic train control and a portion not so equipped, car-carried means for controlling the vehicle brakes in accordance with influences corresponding to traffic conditions while the vehicle is traveling in said equipped portion and for maintaining the brake control apparatus inactive when traveling in the unequipped portion of trackway comprising, a main relay energized in accordance with control energy received from the track rails by inductive receiving apparatus, a brake control device normally controlled by said main relay, a manually energizable relay acting when energized to reduce the sensitivity of the inductive receiving apparatus, a secondary relay controlled by said manually energized relay and a non-control relay acting when energized to maintain said brake control device inactive.
10. In an automatic train control system for a railway having a portion of its trackway equipped for automatic train control and a portion not so equipped, a car-carried brake applying device and means for controlling said device in accordance with influences corresponding to traffic conditions inductively received from the trackway in said equipped portion comprising, a main relay and a receiving circuit, a non-control relay acting when energized to maintain said brake applying device inactive in said unequipped portions of trackway, and a secondary relay controlling, and controlled by, said main relay, whereby said non-control relay is energized if said main relay is first de-energized and then re-energized.
11. In an automatic train control system for a railway having a portion of its trackway equipped for automatic train control and a portion not so equipped, car-carried brake control apparatus continuously controlled in accordance with energy received from the trackway through receiving equipment including a transformer, and means to change the connections of said transformer in said receiving equipment and thereby reduce the sensitivity of said receiving equipment.
12. In an automatic train control system for a railway having a portion of its trackway equipped for automatic train control and a portion not so equipped, car-carried brake control apparatus continuously controlled in accordance with energy received from the trackway through receiving equipment including a transformer, and means to change the connections of said transformer in said receiving equipment and thereby reduce the sensitivity of said receiving equipment, means at the entrance to said unequipped portion of trackway for delivering an excessive amount of energy to said receiving equipment, and means for maintaining said brake control apparatus

inactive, while traveling in the unequipped portion of trackway, said last mentioned means being actuated if the transformer connections changing means is energized while the vehicle is traversing said excessively energized trackway means.

13. In an automatic train control system for a railway having a portion of its trackway equipped for automatic train control and a portion not so equipped, car-carried brake control apparatus continuously controlled in accordance with energy received from the trackway through receiving equipment including a transformer and an amplifying unit connected thereto, and means for changing the taps of the transformer to which said unit is connected, whereby to vary the sensitivity of said receiving equipment.

14. In an automatic train control system for a railway having a portion of its trackway equipped for automatic train control and a portion not so equipped, car-carried brake control apparatus continuously controlled in accordance with energy received from the trackway through receiving equipment including a transformer and an amplifying unit connected thereto, and manually actuatable means for changing the taps of the transformer to which said unit is connected, whereby to vary the sensitivity of said receiving equipment.

15. In an automatic train control system for a railway having a portion of its trackway equipped for automatic train control and a portion not so equipped, car-carried means for controlling the vehicle brakes in accordance with influences corresponding to traffic conditions while the vehicle is traveling in said equipped portion and for maintaining the brake control apparatus inactive when traveling in the unequipped portion of trackway comprising, a main relay energized in accordance with control energy received from the track rails by inductive receiving apparatus, a brake control device normally controlled by said main relay, a manually energizable relay acting when energized to reduce the sensitivity of the inductive receiving apparatus, a secondary relay controlled by, and in turn controlling, said main relay, and a non-control relay controlled by both the said main relay and secondary relay and acting, when energized, to maintain said brake control device inactive.

16. In an automatic train control system for a railway having a portion of its trackway equipped for automatic train control and a portion not so equipped, car-carried means for controlling the vehicle brakes in accordance with influences corresponding to traffic conditions while the vehicle is traveling in said equipped portion and for maintaining the brake control apparatus inactive

- when traveling in the unequipped portion of trackway comprising, a main relay energized in accordance with control energy received from the track rails by inductive receiving apparatus, a brake control device normally controlled by said main relay, a manually energizable relay acting when energized to reduce the sensitivity of the inductive receiving apparatus, a secondary relay controlled by, and in turn controlling, said main relay, said manually energizable relay operable to simultaneously de-energize said main and secondary relays, said main and secondary relays being timed on drop away characteristics to insure release of said main relay just before the release of said secondary relay, and a non-control relay controlled by both said main relay and secondary relay and acting when energized, to maintain said brake control device inactive.

17. In an automatic train control system for a railway having a portion of its trackway equipped for automatic train control and a portion not so equipped, car-carried means for controlling the vehicle brakes in accordance with influences corresponding to traffic conditions while the vehicle is traveling in said equipped portion and for maintaining the brake control apparatus inactive when traveling in the unequipped portion of trackway comprising, a main relay energized in accordance with control energy received from the track rails by inductive receiving apparatus, a brake control device normally controlled by said main relay, a manually energizable relay acting when energized to reduce the sensitivity of the inductive receiving apparatus, a secondary relay controlled by, and in turn controlling, said main relay, and a non-control relay controlled by both the said main relay and secondary relay and acting, when energized, to maintain said brake control device inactive, said non-control relay being slow to release whereby to prevent its release due to momentary interfering currents on the rails.

18. In an automatic train control system for a railway having a portion of its trackway equipped for automatic train control and a portion not so equipped, car-carried means for controlling the vehicle brakes in accordance with influences corresponding to traffic conditions while the vehicle is traveling in said equipped portion and for maintaining the brake control apparatus inactive when traveling in the unequipped portion of trackway comprising, a main relay energized in accordance with control energy received from the track rails by inductive receiving apparatus, a brake control device normally controlled by said main relay, a manually energizable relay acting when energized to reduce the sensitivity of the inductive receiving apparatus, a secondary relay controlled by, and in turn controlling, said main relay, said manually energizable relay operable to simultaneously de-energize said main and secondary relays, said main and secondary relays being timed on drop away characteristics to insure release of said main relay just before the release of said secondary relay, and a non-control relay controlled by both said main relay and secondary relay and acting when energized, to maintain said brake control device inactive, said non-control relay being slow to release whereby to prevent its release due to momentary interfering currents on the rails.

19. In combination with an electro-responsive device and a source of alternating current, a reactor connected with said device, a condenser connected in parallel with the reactor to tune the reactor to resonance at the frequency of said current, and a circuit for said source including a portion of said reactor and tuned to resonance at the frequency of said current.

20. In combination, a stretch of railway track, means for at times supplying alternating current to the rails of said stretch, an auto transformer having a secondary tuned to resonance at the frequency of such current, an electro-responsive device connected with said secondary, and a pick-up circuit receiving energy from the track rails and including the primary of said transformer and tuned to resonance at the frequency of said current.

21. In combination, a stretch of railway track, means for at times supplying alternating current to the rails of said stretch, an auto transformer having a secondary tuned to parallel resonance at the frequency of said current, a pick-up circuit for the primary of said auto transformer receiving energy from the rails and tuned to series resonance at the frequency of said current, and governing means controlled by energy delivered by the secondary of said auto transformer.

22. In an automatic train control system for a railway having a portion of its trackway equipped for automatic train control and a portion not so equipped, means for automatically controlling the vehicle brakes in accordance with influences corresponding to traffic conditions continuously received from the trackway in said equipped portion including a receiving circuit and an amplifier, and means for rendering said automatic brake control means inactive for vehicle travel in said unequipped portion of trackway including means for causing said amplifier to draw an appreciable current from said receiving circuit and thereby reducing the sensitivity of said receiving circuit.

23. In an automatic train control system for a railway having a portion of its track-

- way equipped for automatic train control and a portion not so equipped, vehicle-carried control apparatus for controlling the vehicle brakes in accordance with influences corresponding to traffic conditions received from the trackway in said equipped portion, receiving equipment including an amplifier and a receiving circuit having transformers of poor regulation therein, and means for maintaining the automatic vehicle brake control apparatus inactive for vehicle travel over said unequipped portion of trackway including a normally de-energized, manually energizable relay, acting when energized to cause said amplifier to draw an appreciable current from said receiving circuit and thereby reducing the amplitude of the energy transmitted by the receiving circuit and the amplifier.
24. In an automatic train control system for railways having a portion of its trackway equipped for automatic train control and a portion not so equipped, a vehicle-carried automatic brake applying device, means for controlling said device when the vehicle is traveling over said equipped portion of trackway comprising, a receiving circuit including a transformer having a poor regulation and connected to the grid-filament circuit of an audion tube amplifier, means for maintaining said automatic brake applying device inactive for vehicle travel over said unequipped portion of trackway comprising a section of trackway at the entrance to said unequipped portion having means for transmitting an excessive amount of energy to said receiving circuit, a normally de-energized manually energizable car-carried relay acting when energized to cause the grid of one tube of said audion tube amplifier to assume a positive potential, thereby causing said amplifier to draw an appreciable current from said receiving circuit and reduce the power transmitted by said receiving circuit, and means for rendering and maintaining said brake applying device inactive if said car-carried relay is energized while the vehicle traverses said excessively energized section, and is de-energized when the vehicle leaves said section.
25. In an automatic train control system for a railway having a portion of its trackway equipped for automatic train control and a portion not so equipped, a vehicle-carried main relay, means comprising a receiving circuit including a plurality of receiving coils for controlling the energization of said main relay while the vehicle is traveling over said equipped portion of trackway, and apparatus for reducing the sensitivity of said receiving circuit so that it will be capable of energizing said main relay only when supplied with an excessive amount of energy from the trackway, said apparatus

including a circuit controller acting when actuated to reduce the number of receiving coils connected in said receiving circuit.

26. In an automatic train control system for a railway having a portion of its trackway equipped for automatic train control and a portion not so equipped, a vehicle-carried automatic brake applying device, means for controlling said brake applying device in accordance with alternating control currents flowing in the track rails in said equipped portion of trackway comprising a receiving circuit including a plurality of receiving coils tuned to resonance at the frequency of said alternating control currents, means for maintaining said brake applying device inactive for vehicle travel in said unequipped portion of trackway including a normally de-energized manually energizable relay, acting when energized to reduce the number of receiving coils in said receiving circuit and to detune said receiving circuit, whereby said receiving circuit may deliver a normal amount of energy is only when an excessive amount of energy is supplied from the trackway, and trackway means at the entrance to said unequipped portion of trackway for supplying an excessive amount of energy to said receiving circuit.

In testimony whereof I hereby affix my signature.

WILLIAM D. HAILES.
